Super Stud, Spec sheet for RC Super resilient channel, undated.
(Continued)*Primary Examiner* — Llorellys Martinez*(74) Attorney, Agent, or Firm* — Notaro, Michalos &
Zaccaria P.C.(57) **CLAIM**The ornamental design for an isolated resilient channel, as
shown and described.

DESCRIPTION

FIG. 1 is a top, front, left isometric view of an isolated
resilient channel, showing our new design.

FIG. 2 is a front elevational view thereof;

FIG. 3 is a rear elevational view thereof;

FIG. 4 is a left elevational view thereof;

FIG. 5 is a right elevational view thereof;

FIG. 6 is a top plan view thereof; and,

FIG. 7 is a bottom plan view thereof.

The broken lines in the drawings represent portions of the
isolated resilient channel that form no part of the claimed
design. The isolated resilient channel is shown with a
symbolic break in its length. The appearance of any portion
of the isolated resilient channel between the break lines
forms no part of the claimed design.**1 Claim, 6 Drawing Sheets**(56)
